UNITED STATES PATENT OFFICE.

ROBERT L. MUNDELL, OF OSKALOOSA, IOWA.

RAILWAY-CROSSING SIGNAL.

Application filed May 10, 1924. Serial No. 712,400.

To all whom it may concern:

Be it known that I, ROBERT L. MUNDELL, a citizen of the United States of America, residing at Oskaloosa, in the county of 5 M^ahaska and State of Iowa, have invented certain new and useful Improvements in Railway-Crossing Signals; and I do hereby declare that the following is a full, clear, concise, and exact description of the invention, such as will enable others skilled in the 10 art to which it appertains to make and use the same.

This invention relates to improvements in railway crossing signals, having for an object to provide a mechanical automatic crossing signal adapted to be operated to audibly and visually warn persons of the approach of a train in a timely manner, the invention including a novel form of trip actuated motion transmitting means whereby the audible and visual alarms are caused to operate with movement of the wheels of a train thereover.

It is likewise an object of the invention to provide a railway crossing signal employing a novel form of audible and visual signalling means, the same being collectively operable through connection with the trip actuated motion transmitting means in a manner to attract and stay the attention of traffic at or in proximity to the equipped railway crossing.

Other objects of the invention will be in part obvious, and in part pointed out hereinafter.

In order that the invention and its mode of operation may be readily understood by persons skilled in the art, I have in the accompanying illustrative drawings, and in the detailed following description based 35 thereupon, set out one possible embodiment of the same.

In these drawings:—

Figure 1 is a plan view of the improved signal arranged in operative position at a 45 railway crossing;

Figure 2 is a fragmentary side elevation of the same;

Figure 3 is a fragmentary enlarged detail in section showing the mounting of the trip 50 actuated arm adjacent one of the railway tracks; and,

Figure 4 is an end elevation of the trip actuated motion transmitting and converting means.

Having more particular reference to the drawings, in connection with which like

characters of reference will designate corresponding parts throughout, 1 represents the parallel tracks of a railway which intersect a roadway designated in its entirety herein 60 by the numeral 2.

The improved crossing signal may be stated to comprise a supporting frame consisting of vertically and horizontally arranged bars, rods, or other suitable devices 65 indicated in its entirety by the numeral 3', such frame being arranged at a point sufficient distant from the railway crossing and having opposed balls 3 fixedly mounted upon the upper portion thereof, while a striking 70 hammer 4 is pivotally mounted upon one of the horizontal members of said frame 3' as is indicated at 5. A laterally extending supporting arm or bracket 6 is arranged upon that portion of the frame 3' adjacent the 75 corresponding side of the roadway 2 and supports thereon a figure 7, simulating a traffic officer. One of the arms of this figure 7, namely, the arm indicated by the numeral 8 is pivotally mounted upon the body 80 and adjacent the shoulder of said figure 7, as is indicated at 9, and has a portion of the same extended and connected to a rod 10 pivotally connected at its remaining end to the lower portion of the bell striking hammer 4 as indicated at 11. Thus, it will be seen that the visual and audible signals constituted by the arm 8 and the bells 3 are collectively operable.

With a view towards providing means 90 for effectually operating the audible and visual signals aforesaid, supporting arms 12 and 13 are secured to extended portions of certain of the sleepers or ties of the railway track 1, as is clearly shown in the Figure 95 1, preferably by spikes or similar fastening devices 14. The inner ends of these arms 12 are curved upwardly, as is indicated by the numeral 14' and engage with the web portions of the adjacent railway 100 tracks in the manner shown in the Figure 3, the adjacent marginal portions of such curved portions 14' of the arms 12 and 13 engaging directly under the tread portions of the railway tracks. A bracing arm or 105 bar curved longitudinally upon itself and indicated by the numeral 15, is arranged transversely of the curved ends 14' of the arms 12 and 13 and is joined to adjacent portions of such arms through the medium 110 of bolts or other suitable fastening devices 16. Vertically positioned bearing brackets

17 are secured to portions of the arms 12 and 13 in proximity to the upward curved ends 14' of the same and receive therebetween a supporting rod 18 upon which an adjacent portion of a trip arm 19 is pivotally mounted, as indicated at 20. The inner end of the trip arm 19, that is, the end adjacent the railway track heretofore referred to, is upturned, or disposed at substantially right angles, as indicated at 21, this latter portion being adapted to be arranged in immediate proximity to the tread portions of said railway track and to be normally extended for a distance slightly 15 above the same as is clearly shown in the Figures 3 and 4. To limit this upward movement of the inner end of the trip arm 19 carrying the right angularly disposed finger 21, a stop bar or rod 22 is secured at 20 its opposite extremity to adjacent portions of the bars 15 and by being arranged directly over the adjacent portion of said trip arm 19, of course, will serve to limit its upward movement and in consequence, ensure 25 proper positioning of the trip finger 21 with respect to the railway track tread.

The outer portion of the trip arm 19 is bent or curved upwardly, as indicated by the numeral 19' and is formed with a laterally extending extremity, adapted to be connected through the medium of a bracket 23 to the adjacent end of a connecting rod 24, the purpose of which will be presently apparent.

35 A standard 25 is immovably mounted upon the outer end of the arm 12 and pivotally supports upon its upper portion a bell crank lever 26, having one end thereof connected to a bell crank lever 27 to the adjacent end of the connecting rod 24, while the opposite end of the same is connected to a motion transmitting rod 28, such rod having its opposite extremity pivotally connected to the lower end of the bell striking hammer 4, this latter being retained in its 40 normal position through the medium of a contractile coiled spring 29 connected at one end to the same, while its remaining end is connected to an adjacent portion of the supporting frame 3'. Thus, it will be understood that with depression of the trip finger 21, the trip arm 19 will be rocked, thereby causing upward movement of the curved extremity 19' of the same and imparting a rocking motion to the bell crank lever 26, whereupon such motion will be converted into a reciprocatory motion and transmitted by way of the rod 28 to the pivotally mounted bell striking hammer 4. 45 Hence, the hammer 4 will alternately strike the opposed bells 3 and additionally, will effect pivotal movement of the signalling arm 8 mounted upon the Figure 7. The collective operation of the visual and audible signals will of course continue in so long

as the intermittent engagement of the wheels of the railway rolling stock passing over the railway tracks 1 continue to engage with the trip finger 21 of the trip arm 19.

In order that the trip finger 21 of the trip arm 19 will be normally retained in its extended position whereby to be engaged by the tread portion of railway rolling stock passing over the tracks 1, a contractile coiled spring 30 may be and preferably is 75 connected at one end to the laterally extended curved portion 19' of the arm 19, while its remaining end is connected to an adjacent portion of the arm 13.

To additionally brace the trip actuated means with respect to the adjacent railway track, hooked rods 31 are provided having the hooked ends thereof engaged under and with the basal portions of said railway track, as is clearly shown in the Figures 1 and 3, the outer ends of such rods passing through the apertured ends of a curved bracing bar 32 and having nuts 33 turned into engagement with the same for an obvious purpose. This curved bracing bar 32 is preferably secured by rivets, bolts, or other suitable fastening devices indicated at 33' to adjacent portions of the arms 12 and 13. Thus, means will be provided for rigidifying the arms 12 and 13 and likewise, for positively bracing the trip actuated means against relative movement laterally with respect to the railway track with which they are operatively associated. Consequently, operation of the trip actuated means by engagement with the wheels of rolling stock passing over the tracks 1 will be ensured at all times.

The modus operandi of my improved railway crossing signal may be reviewed as follows:

It is to be understood, of course, that the audible and visual signal means are arranged at a point upon the roadway 2 sufficiently distant from the railway crossing to give timely warning and signal to traffic moving thereover. Also, it is to be understood that the length of the motion transmitting rod 28 is such as to permit the arrangement of the trip actuated means at a point distant from the audible and visual signal means.

With movement of the wheels of a train over the upwardly extended trip finger 21 of the trip arm 19, it will be understood that said finger will be depressed, and in consequence, a rocking motion will be imparted to the trip arm 19 causing a similar motion to be transmitted to the bell crank lever 26 through the medium of the connecting rod 24, which by reason of its connection with the rod 28 will impart a reciprocal motion thereto and in consequence, will operate the pivotally mounted bell striking hammer 4 to alternately strike the

opposed bells 3 and to likewise collectively cause swinging movement of the pivotally mounted signal arm 8 arranged upon the figure 7. In this way, it will be understood that a timely audible and visual signal or warning will be imparted to traffic upon the roadway 2, permitting the same to come to a full stop or to proceed with the necessary caution to avoid accidents.

10 Manifestly, the construction shown is capable of considerable modification, and such modification as is within the scope of my claim, I consider within the spirit of my invention.

15 I claim:—

A railway crossing signal comprising a supporting frame arranged at a point adjacent from the point of intersection of the railway tracks with the roadway, opposed 20 bells immovably supported upon said frame, a figure immovably supported laterally of said frame, a visual signal arm pivotally mounted on said figure, a bell striking hammer pivotally mounted upon the frame and 25 adapted to alternately engage said opposed bells, means for connecting the bell striking hammer to one end of said visual signal arm, supporting arms secured to certain of

the sleepers of the railway tracks, bearings on said supporting arms, a trip arm pivotally mounted between said bearings having one end thereof disposed in proximity to the tread portion of one of the railway tracks and formed with a right angularly disposed trip finger normally extended 35 above the tread portion of said railway tracks, the opposite portion of said trip arm being curved upwardly and formed with a lateral extension, an upright supported upon one of said arms, a bell crank lever 40 mounted upon the upright having one end thereof connected to the lateral extension of said trip arm, a motion transmitting rod connected to the remaining end of said bell crank lever and to one end of the pivotally 45 mounted bell striking hammer, a curved bracing bar arranged transversely of said supporting arms and secured to adjacent portion of the same, and rods having hooked ends engaged in the opposite extremities of 50 said curved bracing bar and connected to the basal portions of said adjacent railway track.

In witness whereof I have hereunto set my hand.

ROBERT L. MUNDELL.
